UNITED STATES PATENT OFFICE.

JOHN T. WILMORE, OF DENVER, COLORADO.

MEANS FOR AUTOMATICALLY CONTROLLING LIQUID-SUPPLY.

No. 909,355.

Specification of Letters Patent.

Patented Jan. 12, 1909.

Application filed February 10, 1908. Serial No. 415,061.

To all whom it may concern:

Be it known that I, JOHN T. WILMORE, a citizen of the United States, residing in the city and county of Denver and State of Colorado, have invented certain new and useful improvements in Means for Automatically Controlling Liquid-Supply; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to means for automatically controlling the supply of liquid to a receptacle, being more especially intended for maintaining acid in a trough at a uniform level in canning factories. It is well known that in canning factories, acid must be applied to the cans before the caps are soldered in place.

The object of my invention is to maintain the acid in the trough or receptacle at a uniform level so that the brush or other device which is used to apply the acid, shall always enter the trough or receptacle at a uniform depth; and to this end I provide a source of supply whose discharge extremity enters a recess which is in communication with the acid trough, the said recess being provided with ribs or beads to prevent the discharge nozzle of the bottle or other device from coming in direct contact with the bottom of the recess which might have a tendency to prevent the escape of the liquid. As soon as the liquid rises in the receptacle to a sufficient depth, to seal the discharge extremity of the supply source, the liquid will cease to flow since no air can enter the receptacle and consequently the liquid will cease to flow until its level in the trough, is lowered sufficiently to permit the entrance of air to the supply source in which event, the liquid will begin to flow and continue so to do until a liquid seal is again formed around the discharge opening of the supply source.

Having briefly outlined my improved construction, I will proceed to describe the same in detail reference being made to the accompanying drawing in which is illustrated an embodiment thereof.

In this drawing, Figure 1 is an elevation partly in section illustrating my improvement shown in connection with the can con-

veyer of a canning factory, the track of the conveyor being shown in cross section. Fig. 2 is a top plan view of the same, the conveyor mechanism being omitted. Fig. 3 is a top view in detail of the acid trough or receptacle.

The same reference characters indicate the same parts in all the views.

Let the numeral 5 designate a vertical rod connected by means of a set bolt 6 with a stationary bracket 7 connected with a track 8 supporting a chain 9 engaging cans 10 whereby the latter are caused to move along the track to the desired location. To the upright rod 5, is secured an acid trough 12 adapted to contain a quantity of liquid 13, the body of the trough being in communication with a recess 14 provided with a number of ribs 15 upon which the nozzle 16 of a bottle 17 rests. This bottle is chosen as a conventional acid-containing device. In the construction shown in the drawing the bottle is inverted and its open neck or nozzle is inserted in the recess 14 and rests upon radially disposed ribs or projections 15, whereby the liquid is allowed to flow freely from the bottle until the trough is filled and the liquid rises in the recess 14 to a sufficient level to seal the nozzle of the bottle.

The trough 12 is provided with an apertured projection 18 through which passes the rod 5, the receptacle being maintained in place in any desired position by means of a set bolt 19.

It will be understood that the acid trough and the source of supply connected therewith may be raised and lowered with reference to the track 8, by loosening the set bolt 6 and moving the rod 5 either up or down in the eye 4 of the bracket 7. By virtue of this adjustment the position of the trough and source of supply may be accurately regulated with reference to the height of the can top to which the acid is to be applied.

The bottle 17 containing a quantity of acid may be supported in the inverted vertical position by means of curved arms 20 and 21, each of which is connected at one extremity with a sleeve 22 slidable on the rod 5 and held in the desired position of adjustment by a set bolt 23. These arms pass part way around the bottle in opposite directions from the sleeve. The arm 21 is provided with an inwardly projecting lug 24 adapted to engage the bottle 17. The arm 20 is provided at its free extremity with a

threaded opening in which is inserted a set screw 25 which may be screwed to engagement with the bottle. The sleeve 22, is also provided with an inwardly projecting lug 26 adapted to engage the bottle. The two arms 20 and 21 taken together pass more than half way around the bottle and when the set screw is properly adjusted, the bottle is securely supported in the inverted 10 vertical position.

From the foregoing description the use and operation of my improved device will be readily understood. Assuming that the acid trough and the bottle-supporting device are 15 properly adjusted upon the rod 5 and that the latter is properly adjusted with reference to the tops of the cans carried by the conveyer, the operation is as follows: The liquid first flows freely from the open nozzle of the 20 bottle 17 into the recess 14 and thence into the acid trough or receptacle 12 until the latter is filled and the liquid rises in the recess 14 to a height sufficient to seal the opening of the nozzle 16 from the entrance of air. 25 The liquid will then cease to flow until it has been lowered in the trough or receptacle sufficiently to allow the air to enter the bottle and break the vacuum above the liquid. The latter will then continue to flow into 30 the recess and thence into the trough or receptacle 12 until a liquid seal is again formed around the discharge nozzle of the bottle or other source of supply, after which the liquid will cease to flow until it is again lowered in 35 the trough after which the operation is automatically repeated.

Having thus described my invention, what I claim is:

1. In apparatus of the class described, the 40 combination with a stationary support, of a supporting rod vertically adjustable on said support, a liquid-containing trough mounted on the support and having a recess located beyond the body of the trough but in communication therewith, a liquid-containing 45 receptacle having its discharge extremity

entering the said recess in position to allow the liquid to flow from the receptacle into the said recess, means for maintaining the liquid-containing receptacle in the position 50 of discharge whereby the liquid will flow therefrom into the recess until the liquid rises in the trough sufficiently to seal the discharge extremity of the liquid-containing receptacle, substantially as described. 55

2. The combination with a stationary support, of a vertically disposed rod mounted on said support, an acid trough attached to the support and vertically adjustable thereon, a liquid-containing receptacle having its discharge extremity projecting into the trough, whereby the liquid is allowed to flow freely 60 into the trough until it rises sufficiently to seal the discharge extremity of the source of supply, and arms mounted on the supporting 65 rod and embracing the liquid-containing receptacle for maintaining the latter in position of discharge with reference to said trough, substantially as described.

3. The combination with a stationary 70 member, of a vertically disposed supporting rod attached to the said stationary member, an acid trough vertically adjustable on the said rod, a supply source having a discharge nozzle projecting into the trough, and arms 75 vertically adjustable upon the supporting rod and embracing the source of supply whereby the latter is maintained in the position of discharge, substantially as described.

4. The combination with a conveyer track, 80 of an acid trough connected therewith and arranged at one side thereof, a supply source having a discharge nozzle projecting into the trough, and arms for supporting the supply source in the discharge position, substan- 85 tially as described.

In testimony whereof I affix my signature in presence of two witnesses.

JOHN T. WILMORE:
